UNITED STATES PATENT OFFICE.

CHARLES F. STRAUSBAUGH, OF DETROIT, MICHIGAN.

MOLD-CORE.

1,371,525.

Specification of Letters Patent. Patented Mar. 15, 1921.

Application filed June 11, 1920. Serial No. 388,251.

To all whom it may concern:

Be it known that I, CHARLES F. STRAUSBAUGH, a citizen of the United States of America, residing at Detroit, in the county 5 of Wayne and State of Michigan, have invented certain new and useful Improvements in Mold-Cores, of which the following is a specification, reference being had therein to the accompanying drawings.

10 In the construction of hollow walls, chimneys, conduits and other hollow structures, it is often necessary to use collapsible cores, especially when the hollow structures are made of concrete or other plastic material, 15 and in the use of such cores it is essential that the parts of the cores be assembled so as to provide rigid and durable forms about which the concrete or other plastic material may be tamped to solidify without 20 any danger of the walls of the core collapsing. It is furthermore essential that the parts of the core be constructively arranged so as to facilitate assembling and disassembling without any undue binding action of 25 one part of the core relative to other parts thereof.

My invention aims to provide a collapsible core wherein positive and reliable means are employed, in a manner as hereinafter 30 set forth, for interlocking the parts of the core so that the same cannot become accidentally displaced due to any pressure or strains on the parts of the core during its use. The manner of interlocking or articulating the core parts permits of the core parts being easily and quickly assembled and disassembled, and provision is made for placing the cores in superposed relation for the construction of a wall or chimney of 35 considerable height, the cores being arranged to provide clearance for tie members that may be employed between the walls of the hollow structures.

My invention further aims to provide a 40 collapsible mold core having parts that may be constructed of solid material provided with suitable facings to withstand wear and tear incident to the assembling and disassembling of the mold parts. In lieu of the 45 solid material entering into the core part, each part may be fabricated from structural metal or other material and suitably trussed or braced throughout to have the same firmness as though solid.

50 My invention still further aims to provide a strong, durable and inexpensive mold core

that may be of various shapes and sizes according to the structure to be made hollow by the use of the core, and the mechanical construction entering into the core will be 60 hereinafter specifically described and then claimed.

Reference will now be had to the drawings, wherein—

Figure 1 is a perspective view of the mold 65 core;

Fig. 2 is a plan of the same;

Fig. 3 is a side elevation of portions of cores placed in superposed relation;

Fig. 4 is a horizontal sectional view of 70 the mold core showing solid mold parts or members provided with interlocking facing strips;

Fig. 5 is a similar view showing core members fabricated from structural steel 75 or other material;

Fig. 6 is a perspective view of a foundation member of a core;

Figs. 7 and 8 are perspective views of adjoining members for the foundation mem- 80 ber;

Fig. 9 is a perspective view of a keyed member which interlocks all of the core members;

Fig. 10 is a horizontal sectional view of 85 the mold core taken on the line X—X of Fig. 3;

Fig. 11 is an elevation of an adjoining member interlocked with the foundation member;

Fig. 12 is a similar view of the other adjoining members interlocked with the foundation member;

Fig. 13 is a plan of a mold core that is oblong and designed for forming a hollow 95 wall, and

Fig. 14 is a side elevation of the same.

The mold core to be herein described is of the same cross sectional area throughout its length, and by reference to Fig. 1 it will be 100 noted that the assembled core members provide an oblong structure having opposed walls in parallelism and the end walls in parallel planes at a right angle to the side walls of the core. As the mold core has its 105 members interlocked by a keyed member necessitating the assembling of the core parts in a predetermined manner, the core parts or members will be considered in their order, that is, the order of assembling.

Considering the foundation member reference will be had to Figs. 6, 10, 11 and 12.

This member has walls 1, 2, 3, and 4 with the walls 1 and 2 in planes at a right angle to each other and the walls 3 and 4 tapering inwardly from the lower end of the foundation member to the upper end thereof, so that the cross sectional area of said member gradually decreases from the bottom or base of the member to the top thereof. On the tapered wall 3 is a dovetailed tongue 5 and 10. on the tapered wall 4 is a dovetailed tongue 6. These tongues also taper inwardly from the lower end of the foundation member to the upper end thereof and said tongues are disposed at an angle to the longitudinal 15 edges of the tapered walls 3 and 4. At the juncture of the walls 3 and 4 there is the longitudinal slot 7 communicating with a longitudinal recess in the foundation member, said slot or recess being approximately 20 throughout the length of the foundation member with the slot and recess tapering inwardly from the upper end of the foundation member to the lower end thereof so that any structure which enters the slot and recess 25 must be placed therein at the upper end of the foundation member.

On the lower end of the foundation member is a base piece 9 affording lateral ledges at the lower ends of the tapered walls 3 and 30 4, and adjacent an edge of the base piece 9 and in the bottom thereof is a groove 10.

On the upper end of the foundation member 1 is a flat enlargement 11 having a dovetailed groove 12 adjacent that end thereof flush with the wall 1 of the foundation member, and detachably mounted in the dovetailed groove 12 is the tongue 13 of a spacing member 14 having a hinged section or gate 15. The purpose of the spacing member 14 will be more fully considered after 40 describing other members of the core.

The adjoining members for the foundation member are shown in Figs. 7 and 8, and considering the member of Fig. 7, the first 45 to be placed in engagement with the foundation member, said adjoining member is raised and its lower end placed in engagement with the upper end of the foundation member so that it may be shifted downwardly on the wall 4 of said foundation member. The adjoining member has walls 16 and 17 with the planes thereof at a right angle to each other similar to the walls 1 and 2 of the foundation member, and in addition 50 to the walls 16 and 17 there are tapered walls 18 and 19. The tapered wall 18 is tapered inwardly from the upper end of the member to the lower end thereof and corresponds to the taper of the wall 4 of the foundation member, so that when the walls 4 and 18 55 are in abutting relation the wall 17 of the adjoining member will be in parallelism with the wall 2 of the foundation member. The tapered wall 18 has a dove-tailed groove 20 disposed at an angle to the edges of the wall 65

18 and tapered inwardly from the lower end of the member to the upper end thereof so that the groove will correspond to the tongue 6 on the wall 4 of the foundation member and may receive said tongue as the adjoining member is shifted downwardly on the foundation member.

The wall 19 of the adjoining member tapers inwardly from the lower end thereof to the upper end of said member and said wall is provided with a dove-tail longitudinal groove 21 which tapers inwardly from the upper end of said member to the lower end thereof, as clearly shown in Figs. 7 and 11. This groove has its center line parallel 80 to that edge of the tapered wall 19 adjoining the tapered wall 18, and this groove receives a portion of the key member which will be hereinafter referred to.

On the lower end of the adjoining member 85 is a base piece 22 of less area than the lower end of said member and providing a ledge projecting from the lower end of the tapered wall 19. This base piece serves as a continuation of the base piece 9 of the foundation 90 member when the adjoining member is placed in engagement therewith, and said base piece has a groove 23 in its lower face which alines with the groove 10 in the lower face of the base piece 9.

On the upper end of the adjoining member 95 is an enlargement 24 having a projecting portion 25 adapted to overlap the upper end of the foundation member and abut the flat enlargement 11 thereon. Connected to 100 the enlargement 24 by a tongue and groove connection is a spacing member 26 and one end of said spacing member is beveled, as at 27 so as to receive the section or gate 15 of the spacing member 14 of the foundation 105 member. The spacing member 26 of the adjoining member serves as a continuation of the spacing member 14 of the foundation member, and these spacing members have the upper edges thereof provided with a 110 longitudinal tongue 28 adapted to fit in grooves 10 and 23 of a core placed on the spacing member, as shown in Fig. 3, thus permitting of superposed cores being interlocked against lateral displacement with a 115 space between the confronting ends of the superposed cores.

Considering the other adjoining member best shown in Fig. 8 there are walls 29 and 30 disposed in planes at a right angle to 120 each other and tapered walls 31 and 32. The wall 31 is tapered inwardly from the upper end of the member to the lower end thereof and is provided with a tapered dove-tail groove 33 corresponding in angularity 125 to the tongue 5 of the wall 3 of the foundation member so that the walls 3 and 31 may be placed in abutting interlocked relation. The wall 32 is tapered inwardly from the lower end of the adjoining member to the 130

upper end thereof and this wall has a longitudinal dove-tailed tongue 34 with its center line parallel to that edge of the wall 32 adjoining the wall 31.

5 The lower end of the adjoining member has a base plate 35 as a continuation of the base piece 9 and the lower face of the base piece 35 has a groove 36 adjacent its side edge. The upper end of the adjoining member has a flat enlargement 37 provided with a projecting portion 38 adapted to overlap the upper end of the foundation member and abut the enlargement 11 thereof. The enlargement 37 has a detachable spacing member, and a hinged section, generally designated 39, that are similar to the spacing member 14 of the foundation member.

10 The last member of the core to be assembled is the key member shown in Fig. 9, which has walls 40 and 41 in planes at a right angle to each other and these walls cooperate with the walls 1, 2, 16, 17, 29 and 30 of the other core members in providing a core that has exterior walls in parallel planes at a right angle to each other as best brought out in Figs. 1 and 10. In addition to the walls 40 and 41 there are tapered walls 42 and 43 both of which taper inwardly from the upper end of the key member to the lower end thereof and correspond in inclination to the walls 32 and 19 of the adjoining members. The tapered wall 42 has a longitudinal dove-tailed groove 44 to receive the tongue 34 of the wall 32 and the wall 43 has a tapered dove-tailed tongue 45 to fit in the groove 21 of the wall 19. At the juncture of the tapered walls 42 and 43 there is a longitudinal tapered key 46 adjoining the key member by a neck portion 47 and the key 46 tapers inwardly from the upper end of the key member to the lower end thereof so that said key and its neck portion may be placed in the recess 8 and the slot 7 of the foundation member and thus interlock the four members of the core through the medium of the tongue and groove connections between the confronting faces or walls of the assembled core members.

15 On the lower end of the key member is a base piece 48 having a groove 49 and this base piece serves as a continuation of the base piece 35 with the groove 49 alining with the groove 36 of said base piece. It is now apparent that the base pieces 22, 35 and 48 coöperate with the base piece 9 of the foundation member in providing a sectional base or footing for the core and the grooves 36 and 49 serve the same purpose as the grooves 10 and 23 heretofore described in connection

20 with Fig. 3 of the drawing.

25 On the upper end of the key member is a comparatively large flat enlargement 50 having projecting portions that overlap the upper ends of the adjoining members and coöperate with the enlargements 11, 24, and

38 in forming somewhat of a cap on the top of the core. The enlargement 50 of the key member has its edge thereof provided with a spacing member 51 which coöperates with the spacing member 39 in providing a spacing member in opposed relation to the spacing members 14 and 26, and as heretofore mentioned the spacing members coöperate in supporting another core in spaced relation to the supporting core.

30 In the construction of a hollow wall or any large structure necessitating outer mold walls 52, as indicated by dot and dash lines in Fig. 13, it is often necessary to use transverse braces, tie rods or similar members 53 and the spacing members 14, 26, 39 and 51 on the upper end of each core provide clearance for the braces 53, which may be laterally withdrawn from a finished wall or structure. To insure proper spacing of 35 the braces the spacing members may have the ends thereof cut away or recessed, as at 54 (see Figs. 1 and 14) to receive the braces 53, and the holes left in a wall by the withdrawal of the braces may be closed as the 40 construction of the wall progresses. Fig. 13 also brings out the fact that the core members may be oblong in plan or horizontal section, in contradistinction to the shape shown in Fig. 10, so that the members may 45 be used to form a trough or hollow wall.

40 The spring members and the hinged sections or gates thereof coöperate in providing releasing means from adjoining members and also retaining means by extending over 100 portions of the key member.

45 As brought out in Figs. 4 and 10 the core members are made of solid material and when such material as wood is employed the confronting interlocking faces or walls 105 of the core members may be provided with facing strips 55, made of metal, to afford tongues, grooves, a recess and a key for interlocking the core members. With the facing strips made of metal the body of each 110 core member is not subjected to wear and tear during the assembling or disassembling of the mold core members.

50 Instead of making the core members of solid material it is possible to construct the 115 same of structural steel, as shown in Fig. 5, so that each core member will be hollow and may be trussed or braced, as generally indicated at 56. With these core members made of pressed steel or similar metal it is 120 possible to shape the walls thereof so as to afford the necessary interlocking tongue and groove connections between the core members.

55 It is thought that the utility of my collapsible core will be apparent without further description, and while in the drawings there are illustrated the preferred embodiments of my invention, it is to be understood that the structural elements are sus- 125

ceptible to such changes in size, shape and manner of assemblage as fall within the scope of the appended claims.

What I claim is:—

5. 1. A mold core composed of members having interlocked confronting faces, and spacing members on the upper ends of said interlocked members.
10. 2. A mold core as characterized in claim 1 wherein one of said members serves as a key for interlocking all of the other members.
15. 3. Superposed mold cores, each composed of interlocked members, spacing members on the upper ends of said interlocked members, and base pieces on the lower ends of said interlocked members adapted to receive the spacing members of an adjacent core.
20. 4. A mold core composed of a foundation member, adjoining members, and a key member, said key member engaging in said foundation member, and said adjoining members having tongue and groove connections with said foundation member.
25. 5. A mold core as characterized in claim 4, wherein said key member has a key and neck portion fitting in a recess and slot of said foundation member.
30. 6. A mold core composed of a foundation member, adjoining members, and a key member, tongue and groove connections between said foundation and adjoining members, tongue and groove connections between said key and adjoining members, and a key connection between said key and foundation members.
35. 7. A mold core as characterized in claim 6 wherein the tongue and groove connections of said foundation and adjoining members are tapered inwardly from the lower end of the core to the upper end thereof and disposed at an angle to the outer walls of the foundation member.
40. 8. A mold core as characterized in claim 6, wherein the tongue and groove connec-

tions of said key and adjoining members are tapered inwardly from the upper end of said core to the lower end thereof and disposed parallel to inner walls of said key member.

50

9. A mold core as characterized in claim 9, wherein spacing members are detachably mounted on the upper end of said core to engage in the lower end of a superposed core to maintain the adjacent cores in spaced relation.

55

10. A mold core comprising a foundation member having tapered walls with a recess at the juncture of said walls, adjoining members having tapered walls with some of said walls engaging the tapered walls of said foundation member, a key member having tapered walls to engage the other tapered walls of said adjoining members, and a key carried by said key member to engage in the recess of said foundation member.

60

11. A mold core as characterized in claim 11, wherein tongues and grooves connect the tapering walls of all of said members.

12. A mold core comprising separable members, spacing members carried by said separable members, and hinged gates carried by said spacing members, and extending on certain of said separable members to preclude removal of said members until said 75 gates are removed.

70

13. A mold core comprising a foundation member, adjoining members, a key member having an upper end overlapping said foundation and adjoining members, and retaining means in an adjoining member extending on to said key member to lock said key member in engagement with said foundation and adjoining members.

80

In testimony whereof I affix my signature 85 in the presence of two witnesses.

CHARLES F. STRAUSBAUGH.
